UNITED STATES PATENT OFFICE.

WILLIAM H. BRIDGES, OF GRAND RAPIDS, MICHIGAN, ASSIGNOR TO BENJAMIN FELD,
OF FULTON COUNTY, GEORGIA.

TOILET-BRUSH.

1,272,907.

Specification of Letters Patent. Patented July 16, 1918.

Application filed July 17, 1915, Serial No. 40,523. Renewed May 13, 1918. Serial No. 234,340.

To all whom it may concern:

Be it known that I, WILLIAM H. BRIDGES, a citizen of the United States, residing at Grand Rapids, in the county of Kent and State of Michigan, have invented certain new and useful Improvements in Toilet-Brushes, of which the following is a specification.

My invention relates to improvements in 10 toilet brushes, and its objects are: first, to provide a means whereby the bristles may be folded practically flatwise of the back and with the ends wholly below the front surface of the brush frame; second, to provide a 15 means whereby when the handle of a toilet brush having folding bristle holders is drawn backward from the brush frame a space will be made sufficiently long to allow the bristles to fold downward between the 20 inner end of the handle and the first bristle holder; third, to so construct a brush of the kind mentioned that when the handle is moved forward into the frame and the bristles are positioned at right angles with 25 the frame there will be no space left between the end of the handle and the bristles; fourth, to provide a means whereby one end of the bristle holder frame will be drawn back into the brush frame when the handle 30 is drawn outward and the bristles are folded into the brush frame, and will be moved forward in the brush frame when the handle is moved into the frame to force the bristles out at right angles with the brush frame, 35 and, fifth, to provide a means whereby the handle in a brush of the kind named may be readily locked in place when the bristles are in position for use, and unlocked when it is desired to fold the bristles within the brush 40 frame.

I attain these objects by the mechanism illustrated in the accompanying drawing, in which Figure 1 is a plan of the brush with the bristles removed from the bristle-holders; Fig. 2 is a longitudinal section of the brush frame practically on the line $x-x$ of Fig. 1 showing the form and position of the plate that actuates the bristle holders; Fig. 3 is a side elevation of the metal frame 45 that actuates the plate that actuates the bristle holders; Fig. 4 is a plan of the same; Fig. 5 is a plan of the plate that carries the bristle holders; Fig. 6 is a transverse section of the brush frame practically on the line $y-y$ of Fig. 1; Fig. 7 is a longitudinal section 50

of the brush frame practically on the line $z-z$ of Fig. 1, showing the bristles and bristle holders in folded positions; Fig. 8 is a like sectional view of the brush frame with the bristles at right angles with the frame and the handle locked in place to hold the bristles 60 in working position.

Similar letters refer to similar parts throughout the several views.

In the construction of this brush I form a 65 frame, A, preferably of metal, practically of the form shown in Fig. 1 except that an inwardly extending flange, a, is formed at the outer edges of the side rims as indicated in Figs. 2, 6, 7 and 8, of sufficient width to cover 70 the edges of the bristle holder plates F and G, as indicated in Fig. 6.

The plates G that support the bristle holders, are pivotally connected at one end with the sides of the frame, as at g, so that 75 the opposite ends may be moved toward and from the open face or front of the frame for carrying the bristles outward or inward in the frame, as may be desired. These plates have a series of round holes, as e, through 80 them for the reception of the pivot pins j at the lower edges of the bristle holders E. The plates G, G are pivoted to the sides of the frame by passing the screws g, g through the sides of the frame and screwing them 85 into the holes e' in said plates.

Sliding plates F, F are placed in the frame between the ends of the bristle holders E and the plates G, G and are provided with right angled slots, as f, f', through which 90 the pivot pins j extends. The action of these plates is as follows: While the pins or bearings j, at the lower edges of the bristle holders E pass through the slots f-f' into the holes e in the plates G, G the pins or 95 bearings j', at the upper edges of the bristle holders E, being shorter than the pins j, simply pass through the portions f of the slots f-f' and as the plates F F are drawn backward in the frame A the portions f' of 100 the slots allow the plates to move past the pins j and the pins j' are caused to slide downward in the slots f.

The lower edges of the bristle holders being anchored in the holes e, the bristle 105 holders will be forced to swing on the pins j j and pivots so the bristles K will be carried to the position represented in Fig. 7, or folded inside of the frame A. The opposite movement of the plates F, F will carry 110

the bristles back into the position indicated in Fig. 8, by a simple reverse action of the pins *j* and *j'* in the slots *f-f'* and the holes *e*. The positions of the pins *j* in the portion 5 *f'* of the slots *f-f'* causes the plates *F* and *G* to be always held in the same relative positions laterally so that the free ends of these plates must always move relatively upward and downward together.

10 The bristle holders *E* are held in normal position, with the bristles at right angles to the frame, by the use of a suitable spring, as indicated at *L* in Figs. 6, 7 and 8, and the bristle holders are thrown over to carry the 15 bristles to the position shown in Fig. 7 by pulling the handle *B* longitudinally away from the body *A*. For the purpose of forming a space between the end of the handle and the first adjacent bristle holder to receive the 20 bristles carried by said holder a short slot, as *f''*, is formed in the end of each of the slides *F*, *F* in which the pins or screws *c*, which are screwed into the side arms of the metal frame *C* at each side 25 thereof are made to travel. The slots *f''* are made upon an incline so that when the handle *B* is drawn outward from the body *A* the ends of the plates *F* and *G* will be carried downward so that the bristle holders will 30 be held in a row diagonally of the sides of the brush frame so that all points of the bristles may be stored below the edges of the sides of the frame.

The metal frame *C* is made to fit closely, 35 and yet to slide freely between the two sides of the frame *A*, and should extend far enough into the frame to insure a strong support for the handle *B*, to which it is firmly secured, as by the screws *b*, *b*, as 40 indicated in Fig. 1.

To hold the handle firmly in place when in position to cause the bristles to stand at right angles with the brush frame, I pivotally secure a latch *H* to the support *C'*, of 45 the frame *C*, as at *h*, so the hook *i* at the inner end will engage a properly arranged opening in the back of the brush frame, as indicated in Fig. 8, and form a right angled handle having a button *I* at the other end 50 in position so that by pressing downward on the button the hook *i* will be drawn out of its opening to permit the handle to be drawn away from the frame, as hereinbefore stated, and for the purpose set forth. 55 *i'* represents a spring for holding the latch in normal position with the hook *i* against the surface of the back of the frame *A*, and forcing it through the opening in said back, as indicated in Fig. 8. This means of securing 60 the handle *B* in the desired position is given only as an illustration of how the result may be attained, and not as the only means by which it may be done, or as the means exclusively adopted by me for the 65 purpose.

I prefer that the pins *j* on the bristle holder *E*, that are designed to enter the holes *e-e* in the plates *G*, *G* be integral, or in one piece or in other words, that a rod *J* be passed through the entire length of the 70 bristle holder with the ends projecting far enough to form said pins or bearings *j*, *j*.

It will be readily understood that with all of the bristle holders anchored in the plates *G*, *G* with the pins *j'* engaged in the slots *f*, 75 and the pins *j* engaging the holes *e* in the plates *G*, all the bristle holders must move in unison, and that but one spring *L* will be necessary to carry all bristle holders and bristles into position at right angles with 80 the frame.

What I claim as new, and desire to secure by Letters Patent of the United States, is:

1. In a toilet brush, a sheet metal frame having the sides and one end closed and a 85 narrow rim turned inward from the upper edges of the sides and end, a sheet metal plate pivotally connected at one end to each side of the frame and provided with a series of holes for the reception of the pivotal pins 90 *J* on the bristle holders, bristle holders having two pins projecting outward from each end, a slide at each side of the brush between the ends of the bristle holders and the pivotal plates, and having right angled slots 95 therein, the pivotal pins at the ends of the bristle holders passed through said slots and one of said pins at each end passing through the holes in the pivotal plates forming fixed pivotal bearings for the holders, 100 and the other pins at the ends of the holders made to slide in the vertical arm of the right angled slots, and means for moving the slotted slides endwise to adjust the bristle holders to hold the bristles in different positions.

2. In a toilet brush, a frame made of sheet metal with the sides and one end closed, inwardly extending flanges at the upper edges thereof, a plate pivotally secured at one end 110 to each side of the frame and provided with a line of holes near the lower edges, a slide located at the side of each of the pivotal plates and made longitudinally movable thereon and having right angled slots with 115 the corner openings opposite the holes in the pivotal plates, and also having a diagonal slot near the adjustable end of each slide, bristle holders mounted in said slides by means of a set of pins on each holder passing through the slots in the slides and into the holes in the pivoted plates, and one pair of pins passing through the vertical slots in the inner slides, a longitudinally movable handle slidingly mounted in the frame, pins 120 connected with said handle and passing through the diagonal slots in the slides, in such a manner that the longitudinal movement of the handle will cause the ends of the plates to move laterally and will draw 125 130

the slides longitudinally to adjust the positions of the bristle holders.

3. In a toilet brush, a sheet metal frame having the back, sides and one end closed, 5 plates pivotally connected at one end with the inner surface of the sides and having a line of holes near one edge, longitudinally movable slides connected with the pivotal plates and having properly formed slots 10 therein, bristle holders having pivot-pins projecting from the ends in position to engage the slots in the slides and the holes in the pivoted plates, a longitudinally movable handle so connected with the longitudinally movable slides as to cause the plates to swing on their pivotal bearing and the slides to move longitudinally to adjust the bristle holders to desired positions, and means for locking the handle in position in 15 the frame.

4. In a toilet brush, a frame having the sides and one end closed, a plate pivotally connected at one end with each side of the frame and having a row of holes near one 25 edge, a longitudinally movable slide connected with each of the pivoted plates and having specially formed slots through them, means connected with said pivoted plates to move one end thereof edgewise and the 30 longitudinally movable slides lengthwise, bristle holders so connected with said slides and plates as to be made to revolve part of a revolution by the longitudinal movement of the slides, substantially as, and for the 35 purpose set forth.

5. In a toilet brush, a hollow frame, a plate pivoted at one end to each side of the frame and having a row of holes near one edge, a longitudinally movable slide connected 40 with each of the pivoted plates and having specially formed slots through them, bristle holders, pins at the ends of said bristle holders pivotally connecting them with the pivoted plates, pins at the ends of the bristle 45 holders slidably connected in the slots in the longitudinally movable slides, a handle so connected with the slides and plates as to form or close an opening between the first bristle holder and the end of the handle and 50 at the same time to shift the bristle holders from a right angle to a horizontal position with the back of the brush frame, and to shift the free end of the plates edgewise.

6. In a toilet brush, the combination of 55 a hollow frame, open at one side, two plates arranged within the frame and pivotally connected adjacent one end to opposite edge walls thereof, bristle holders extending transversely across the frame and each having 60 at its ends projections engaging said

plates and constituting pivots for said holders, actuating plates arranged between the pivoted plates and the ends of the bristle holders and provided with slots through which the pivot pins of the bristle holders 65 extend, the actuating plates engaging the bristle holders to turn them about their said pivots, and means for moving the actuating plates to both rock the plates supporting the bristle holders about their pivots and each 70 of the individual holders about its pivotal connection with said plates.

7. In a toilet brush, the combination of a hollow frame, open at one side, two plates arranged within the frame and pivotally 75 connected adjacent one end to opposite edge walls thereof, bristle holders extending transversely across the frame and each having at its ends projections engaging said plates and constituting pivots for said holders, sliding plates arranged between the pivoted plates and the bodies of the bristle 80 holders and provided with slots through which the pivots of said holders extend, means for turning the bristle holders on their 85 pivots as the sliding plates are reciprocated, and means whereby the pivoted plates and bristle holders supported thereby are moved toward and from the open side of the frame as the sliding plates are reciprocated. 90

8. In a toilet brush, the combination of a hollow frame, open at one side, two plates arranged within the frame and pivotally connected adjacent one end to opposite edge 95 walls thereof, bristle holders extending transversely across the frame and each having at both ends two projecting pins, the pins adjacent the closed side of the frame engaging the pivoted plates and constituting pivots for the bristle holders, sliding 100 plates arranged between the pivoted plates and the ends of the bristle holders, and provided with slots through which the pivot pins of the bristle holders extend, whereby the sliding plates may be reciprocated relative to said holders and pivoted plates while 105 connected to the latter by said pivot pins, the sliding plates engaging the other pins on the bristle holders, whereby the several bristle holders will be individually rocked upon 110 their pivots as the sliding plates are reciprocated, and means whereby as the sliding plates are reciprocated all of said parts will be simultaneously moved about the pivots of the pivoted plates toward or from the 115 open space of the frame.

Signed at Grand Rapids, Michigan, July 12, 1915.

WILLIAM H. BRIDGES.
